(No Model.)

S. K. RAHN.

PORTABLE FENCE.

No. 252,621.

Patented Jan. 24, 1882.

UNITED STATES PATENT OFFICE.

SAMUEL K. RAHN, OF WEST ELKTON, OHIO.

PORTABLE FENCE.

SPECIFICATION forming part of Letters Patent No. 252,621, dated January 24, 1882.

Application filed November 8, 1881. (No model.)

To all whom it may concern:

Be it known that I, SAMUEL K. RAHN, of West Elkton, Preble county, Ohio, have invented certain new and useful Improvements 5 in Portable Fences, of which the following is a specification, reference being had to the accompanying drawings, in which—

Figure 1 is a perspective view of one of the main posts; Fig. 2, a perspective view of one 10 of the middle posts, and Fig. 3 an elevation of a panel of complete fence.

The invention pertains to a novel construction of main post, whereby the rail-supports are so formed as not to prevent free access of 15 air to the rail ends, thus greatly guarding against the usual rotting of the rails where they attach to the post; also, to formation of the rail-rests, the brace-loops, the brace-ties, and the stake-loops, whereby the same are formed 20 of a single piece of wire or other suitable flexible material; and, also, to the arrangement of the middle posts, whereby they may be set and the rails attached after the rails are in position.

25 The main post 38 in Fig. 1 is formed of two vertical boards, 1 and 2, united and maintained a proper distance apart by the end pieces, 3. The post is set upon a stone to prevent damaging contact with the damp earth, and braces 30 4 sustain the post in a vertical position.

The rail-rests 41 consist of light iron supports crossing the space between the two boards of which the post is formed. These 35 iron supports rest in holes, as hereinafter explained, in the boards, and the lapping rail ends resting upon them find contact upon very narrow metallic surfaces. Little or no moisture is retained at these contact-points and decay is thus much prevented. The rail-supports 41 40 may of course be formed of separate pieces of iron, and their upper surfaces should be convex, so as to reduce as far as possible the area of contact with the rails. As shown in the drawings, I form these rail-rests of one piece 45 of wire, which is interlaced through holes in the boards; and, furthermore, I cause this same wire to form the brace-loops 24 to retain the top ends of the braces, and also to form brace-ties 42, reaching from the post to the foot of 50 the braces, and also to form stake-loops 25 to receive the brace-stakes 5. In the erection of

the fence no nails need be used. In case the brace-ties 42 are not used, the foot of the post should be staked.

The course of the wire in Fig. 1 is as follows: 55 Starting at one end of the wire at 6, where it joins the brace-tie, it passes around a stake, 5, through hole 7 in foot of the brace, past the junction 6, through hole 8 in board 2, across post-space, through hole 9, thence interlacing 60 in an obvious manner upward and across, passing through holes 10 11 12 13 14 15 16 17, then around a stake-top, then to holes 18 19 20 21 18 19, then around top of rear brace, then through holes 16 17 14, then working downward 65 same as it previously worked upward through holes 15 12 13 10 11 8 9, thence across to foot of front brace, through hole 22, then around stake there located, and finally joining tie at 23. In case stake-loops 25 are omitted, the 70 stakes should be nailed to the brace feet, and, if desired, the ties 42 may attach to the stakes instead of to the braces. If loops 23 and 24 are omitted, the tops of the braces should be nailed or otherwise attached to the posts. 75 Should the two ties 42 be dispensed with, or should they be formed otherwise than from continuations of the main wire, the main wire may make but a single course in its stitching through the post instead of double, as shown. 80 While I use iron wire for the continuous string of this post, other materials may obviously be used, and they may be of a metallic or non-metallic character.

In Fig. 3 is shown a panel of the fence, 38 85 being the main posts; 40, the rails, which may be of rough or dressed lumber, raw timber, or old rails; and 26, the intermediate or middle post, set after the remainder of the fence is erected. It should be here stated that all the wooden 90 parts of this fence may be made of old rails, the neat flat form of upright shown at 1 and 2 in Fig. 1 not being at all essential.

It is obvious that the post 38 cannot be applied as a middle post after the rails are in 95 place without dismantling the post. For this reason the middle post, 26, is formed of a single upright, as shown, and the vertical features of the running wire are utilized to form one side of the rail-retaining elements, as clearly shown 100 in the drawings. The wire may be and must be applied after the post is set. The course

of the wire is the same as in the main posts, 30 and 32 being the loops for the brace-tops, 35 and 36 the rail-receiving elements, and 27 and 37 the brace-ties. The adaptability of the 5 general plan to trellises, &c., as well as fences, is obvious.

I claim as my invention—

1. In a portable fence-post, the combination of two united uprights having a rail-receiving 10 space between them, and a continuous wire stitched through said uprights to form rail-rests, substantially as and for the purpose set forth.

2. The combination, with braces and a fence- 15 post having rail-rests formed by vertical stitches of a continuous wire, of horizontal stitches of said wire near the top of the post to form loops for the tops of the braces, substantially as and for the purpose set forth.

20 3. The combination, with braces and a fence-post having rail-rests formed by stitches of a

continuous wire, of bottom ties formed by outward prolongation of such wire from the bottom of the post to attaching-points near the feet of the braces, substantially as and for the purpose set forth. 25

4. The combination of united uprights 1 and 2, braces 4, stakes 5, and the continuous wire forming rail-rests 41, brace-loops 24, brace-ties 42, and stake-loops 25, substantially as and for 30 the purpose set forth.

5. The combination, with main posts 38 and rails 40, supported by said posts, of the perforated middle post, 26, consisting of a single upright, to which the rails are stitched by a 35 continuous wire, substantially as and for the purpose set forth.

SAMUEL K. RAHN.
